UNITED STATES PATENT OFFICE

CLIFFORD J. WILLIAMS, OF DETROIT, MICHIGAN, ASSIGNOR TO BRIGGS MANUFACTURING COMPANY, OF DETROIT, MICHIGAN, A CORPORATION OF MICHIGAN

DOORLOCK

Application filed February 2, 1925. Serial No. 6,433.

This invention relates generally to latches designed particularly for use with vehicle doors and consists of certain novel features of construction, combinations and arrangements of parts as will be more fully described and particularly pointed out in the appended claims.

In the accompanying drawings;

Figure 1 is a horizontal sectional view through a vehicle door with a latch embodying my invention attached thereto.

Figure 2 is a perspective view of the door latch.

Figure 3 is another perspective view of the door latch.

Figure 4 is a side elevation of the door latch.

Figure 5 is a fragmentary side elevation of the door latch with the outer cover plate removed.

Figure 6 is a side elevation of a slightly modified form of construction.

Figure 7 is a side elevation of another modified form of construction.

Heretofore the case plates of door latches have been mounted upon the inner sides of the doors, and the latching bolts of such latches have been retracted from the outside of the doors by rotatable spindles extending through the doors. With such constructions, the pillars of the doors were usually quite large in cross section to accommodate these spindles, which ordinarily were spaced several inches from the free edges of the doors.

Thus, the vision of the occupants of the vehicle was limited. Furthermore, when the outside operating means extended through the door, the vertically movable glass panels usually provided in the doors had to be relatively narrow so that the movement thereof would not be interrupted by the operating means for the latching bolt. To overcome these objectionable features, I have provided a latch having a case plate that may be attached to a door pillar having a very small cross section. Moreover both the case plate and the outside operating means for the bolt

preferably straddle the guide-way for the vertically movable glass panel, hence the occupants of the vehicle will have an increased

vision and a wider glass panel may be employed.

Referring now to the drawings in which like characters of reference designate corresponding parts throughout the several views, the numeral 1 designates a door, preferably of a vehicle body, having a pillar 2 provided at its inner edge with a channel-shaped portion 3 which constitutes a run-way for a vertically movable glass panel 4.

In order that a suitable latch may be mounted and operated upon the pillar 2 without interfering with the vertical movement of the glass panel, I preferably provide a case plate 5 that is U-shape in cross section and that preferably straddles the channel-shaped guide-way 3. With this construction, the lock is preferably attached to the door by means of suitable headed elements 6 that engage brackets 7, 8, and 9 respectively carried by the inner and outer sections 10 and 11 respectively of the case plate. As shown, the bracket 7 projects laterally from the outer section 11 of the case plate and is preferably attached to the transversely extending portion 12 of the door pillar 2; the bracket 8 is preferably detachably secured to the inner section 10 of the case plate and is secured to the inner side panel of the door; and the bracket 9 is preferably formed integral with the section 10 of the case plate and is also secured to the inner side panel of the door.

Slidably mounted on the inner section 10 of the case plate is a bolt 13, preferably having a shank 14 and an enlarged head 15. As shown, the head 15 is guided by a substantially U-shaped bracket 16 secured to the section 10 of the case plate and is adapted to engage a suitable keeper (not shown) upon the door jamb of the vehicle body, while the shank 14 preferably extends between spaced guide lugs 17 struck out from the section 10 of the case plate and is provided at spaced points throughout its length with a laterally extending lug 18 and a depending extension 19.

To provide a compact construction, the shank 14 is preferably flat so that it may move behind a suitable cover plate 20 secured to the section 10 of the case plate, while a helical spring 21 anchored upon the section 10 of the

the case plate has an arm 22 engaging the inner end of the shank 14 and is adapted to normally hold the bolt in projected position.

For retracting the bolt against the tension 5 of the spring 21, I preferably provide a suitable roll-back 23 that is adapted to be operated from the outside of the door, and a pivoted lever 24 that is adapted to be operated from the inside of the door. As shown, the 10 lever 24 is preferably pivoted at its lower end to the inner section 10 of the case plate, preferably below the bolt shank 14 and extends upwardly beyond the upper edges of the case plate. Intermediate its ends, the 15 lever 24 is preferably provided with an off-set portion 25 that receives the bolt shank 14 and engages the lateral lug 18. To prevent the lever from rattling, a lug 26 is preferably struck out from the inner section 10 of the 20 case plate and serves as a stop for the forward movement of the lever, while a suitable coil spring 27 is preferably terminally secured to the lever and case plate section 10 and normally holds the lever against the lug 25 26. The roll-back 23 is engageable with the depending extension 19 of the bolt shank and is provided with a hub 28 that is journaled in aligned openings in the case plate and cover plate.

30 In order that the bolt 13 may be retracted from outside the door without interfering with the movement of the glass panel in the guide-way, the roll-back 23 is preferably provided at its forward edge with a lateral 35 extension 29 that preferably extends across the transversely extending portion 30 of the case plate and is adapted to be engaged by the lateral extension 31 of a roll-back 32 having a hub 33 journaled in aligned openings in 40 a cover plate 34 and the outer section 11 of the case plate. Any suitable means, (not shown) may be engaged with the square opening 35 in the hub 33 for rocking the roll-back 32 so that the lateral extension 31 there- 45 of will raise the extension 29 of the roll-back 23 and cause the latter to retract the bolt. As shown, the cover plate 34 is provided at its top, bottom and rear edges with inturned flanges 36 that seat against the outer section 50 11 of the case plate and that are preferably provided at spaced points with lugs that engage openings in the case plate section 11 for positioning the cover plate thereon. Thus, with this construction, the roll-back 23 55 may be actuated to retract the bolt without affecting the lever 24 and the latter may in turn be swung to the rear against the lug 18 without affecting the roll-back. The spring 21 will always exert a pressure through the 60 lug on the bolt shank against the lever so that the latter will normally be in operative position to retract the bolt. Likewise the spring will exert a pressure through the depending extension 19 of the bolt shank against the roll-back 23. This action of the spring nor-

mally holds the lateral extension 29 in engagement with the extension 31 so that these parts will normally be in operative position to retract the bolt from the outside of the door. As shown in Figure 5 of the drawings, 70 the roll-back 32 is preferably provided with a depending lug 37 that is engageable with the lower section of the flange 36 of the cover 34 to limit the downward swinging movement of the roll-back extension 31.

75 In order that the outside operating means may be rendered inoperative from the outside of the vehicle, I preferably provide a dog 38 that is pivoted on the outer section 11 of the case plate and is adapted to swing behind a lug 39 on the roll back 32 to prevent the upward swinging movement of the extension 31. This dog 38 is normally held out of the path of the lug 39 against a struck out lug 40 on the case plate section 11, by 80 means of a coil spring 41 anchored on the case plate and may be moved by a suitable means into operative dogging position. As shown, the dog 38 is preferably actuated by a suitable cam 42 rigidly secured to the rotatable 85 cylinder 43 of an auxiliary lock 44 which is preferably anchored in a tubular housing 45 projecting laterally from the cover plate 34. This housing 45 may be secured in any suitable manner to the cover plate 34 and any suitable means such as a screw 46 threadedly engaging the lateral attaching flange 7 on the case plate may be employed for holding the lock 44 within the housing.

90 In the modification illustrated in Figure 6, a dog 50 is adapted to be moved by the inside operating lever 24 into operative dogging position behind a shoulder 51 of the bolt shank 14 for preventing the bolt from being retracted from the outside of the door. As shown, this dog 50 is preferably pivoted on a pin 52 anchored preferably upon the inner section 10 of the case plate, and is normally held out of the path of the bolt shank by 95 means of a suitable spring 53 secured to the case plate. With this construction, the dog 50 may be detachably held in operative dogging position by means of the lever 24. As shown, a suitable leaf spring 55 is anchored upon the inner section 10 of the case plate and is provided intermediate its ends with an embossed rib 56 that is engageable with a suitable depression 57 in the outer face of the lever 24 when the latter is in its forward position. This rib 56 normally serves as an 100 abutment for the forward edge of the lever when in inoperative or neutral position and therefore prevents any objectionable play or rattling thereof. When the dog 50 is in operative position behind the shoulder 51 and the lever 24 is held by the spring 55 in its forward position, the lever may be readily operated from the inside of the vehicle to release the dog 50 and retract the bolt. This may be accomplished by moving the lever to the rear 105 110 115 120 125 130

so that the projection 56 of the spring 55 becomes disengaged from the depression 57, whereupon the spring 53 will automatically move the dog 50 upwardly out of the path of the shoulder 51. The roll-back 23 may then be operated from the outside of the vehicle if desired for retracting the bolt.

In Figure 7 I have shown another modification in which the bolt is retracted from the inside of the door by a vertically arranged rotatable spindle 60. As shown, this spindle is journaled on the inner section 10 of the case plate between spaced struck out bearings 61 and is prevented from moving vertically thereon by a ring 62 that is secured to the spindle preferably at the lower end thereof and extends through elongated openings in the inner section 10 of the case plate and cover plate 20. As shown, this spindle is preferably provided intermediate its ends with a suitable crank portion 64 that engages the lateral projection 18 of the bolt shank 14.

From the foregoing description it will be readily apparent that a latch of this type may be readily mounted upon a door pillar having a very small cross section, consequently the vision of the occupants of the vehicle is materially increased. Moreover, the mechanism for retracting the bolt from the outside of the door straddles the guide-way for the glass panel, hence the vertical movement thereof is not interrupted and a wider panel may be employed. It will also be apparent that the outside operating means and inside operating means may be independently operated for retracting the bolt. Furthermore one of the attaching brackets for the latch also carries the screw 46 that retains the auxiliary lock 44 within the housing 45 on the outside cover plate 34.

While it is believed that from the foregoing description, the nature and advantages of the invention may be readily apparent yet I desire it understood that I do not limit myself to what is herein shown and described and that such action may be resorted to when desired as fall within the scope of what is claimed.

What I claim as my invention is:

1. The combination with a door having a run-way for a vertically movable glass panel, of a latch having a case plate secured to the door, a latching bolt carried by the case plate, and means straddling the run-way and movable along the free edge of the door for operating the bolt from the outside of the door.

2. The combination with a door having a run-way for a vertically movable glass panel, of a latch having a case plate secured to the door, a latching bolt carried by the case plate, a member upon the inside of the door for retracting the bolt, and means movable longitudinally of the door and exteriorly of the run-way for actuating said member from the outside of the door.

3. The combination with a door, and a latch having a case plate secured to the inner side of the door, a latching bolt carried by the case plate, and means for actuating the bolt from the outside of the door including 70 cooperating parts extending across the free edge of the door.

4. The combination with a door having a run-way for a vertically movable glass panel, 75 of a latch having a case plate secured to the door upon the inner side of the run-way, a latching bolt carried by the case plate, and means movable along the free edge of the door and in advance of the run-way for reTRACTING the bolt from the outside of the door.

5. The combination with a door having a run-way for a vertically movable glass panel, 80 of a latch having a case plate secured to said door, a bolt movable over a portion of the case plate, a roll-back upon the inner side of the door for retracting the bolt, and means movable longitudinally and exteriorly of the door and in advance of the run-way for actuating the roll-back to retract the bolt from 85 the outside of the door.

6. The combination with a door having a run-way for a vertically movable glass panel, 90 of a latch having a case plate secured to said door, a bolt carried by the case plate, and means for actuating the bolt from the outside of the door including a roll-back upon the inner side of the door engageable with a projection of the bolt, and a roll-back upon the outer side of the door having a projection engageable with a projection of the roll-back aforesaid.

7. The combination with a door, of a latch having a case plate, brackets projecting from the case plate secured to the door, a latching bolt on the case plate, means for retracting the bolt from the outside of the door, means for rendering the retracting means inoperative including an auxiliary lock on the case plate, and means carried by one of said brackets for holding said auxiliary lock in 100 fixed position on the case plate.

8. The combination with a door, of a latch having a case plate, brackets projecting from the case plate secured to the door, a latching bolt on the case plate, means for retracting the bolt from the outside of the door, means for rendering the retracting means inoperative including an auxiliary lock on the case plate, and an adjustable element carried by 115 one of said brackets for holding said auxiliary lock in fixed position on the case plate.

9. The combination with a door, of a latch having a case plate secured to the inner side of the door, a bolt carried by the case plate, means for actuating the bolt from the outside of the door including a roll-back upon the inner side of the door engageable with a projection of the bolt, and a roll-back located upon the outer side of the door engageable with a projection of the roll-back afore- 120 125 130

said, and means for rendering the first roll-back inoperative including means engageable with a portion of the second roll-back.

10. The combination with a door, of a latch having a case plate secured to the inner side of the door, a bolt carried by the case plate, means for actuating the bolt including a roll back upon the inner side of the door engageable with a projection of the bolt, and a roll-back upon the outer side of the door having a projection engageable with the roll-back aforesaid, and means for rendering the first mentioned roll-back inoperative including a dog upon the outer side of the door engageable with a portion of the last mentioned roll-back.

11. The combination with a door, of a latch having a case plate secured to the inner side of said door, a latching bolt carried by the case plate, a member upon the inside of the door for actuating the bolt, and means for operating said member from the outside of the door including means movable longitudinally of the free edge of the door.

- 25 12. The combination with a door, of a latch having a case plate secured to the inner side of said door, a latching bolt carried by the case plate, a member upon the inside of the door for actuating the bolt, and means for operating said member from the outside of the door including cooperating parts extending across and movable along the free edge of the door.

- 35 13. The combination with a door having a run-way for a movable glass panel, of latch mechanism carried by the door including a roll-back upon one side of the run-way, an operating member upon the opposite side of the run-way, and a connection between said 40 member and roll-back including means located exteriorly of the vertical edge of the door in substantially the horizontal plane of the roll-back.

- 45 14. The combination with a door having a run-way for a movable glass panel, of latch mechanism carried by the door including a latch bolt, and actuating means for the bolt including roll-backs located respectively upon opposite sides of the run-way and having 50 overlapping transversely extending portions in advance of the run-way and exteriorly of the forward edge of the door.

- 55 15. The combination with a door provided at its free vertical edge with a run-way for a movable glass panel of latch mechanism carried by the door including a latch bolt upon one side of the run-way, an operating member upon the opposite side of the run-way and an operating connection between 60 said member and latch bolt extending across the free vertical edge of the door adjacent the jamb face thereof.

In testimony whereof I affix my signature.
CLIFFORD J. WILLIAMS.
